UNITED STATES PATENT OFFICE.

CHARLES SABIERS, OF AMHERST, OHIO.

IGNITION TIMER.

Application filed June 29, 1925. Serial No. 40,329.

The present invention relates to ignition mechanism, and more particularly to timers for use in the ignition systems of internal combustion engines.

5 An object of the invention is to provide an improved rotor for use in the timer to insure the correct firing of the charges in the cylinders and prevent misfiring incident to the jumping or skipping of the wiper member, and to provide a double contact device which further insures the closing of the circuit through the timer.

Another object of the invention is to provide a rotor with a plurality of pairs of contacts with each contact of each pair operable independently of the other so that should one wiper or brush of any pair fail to make contact, the other wiper or brush of the pair may independently operate and effect the necessary contact.

25 A further object of the invention is to provide groups of wipers independently spring pressed into outward position, and to provide means for normally retaining all but one group in retracted position to hold the same in reserve, and to so interconnect the groups as to maintain the desired tension on the exposed group by the retraction of the brushes or wipers which are held in reserve.

30 Another object of the invention is to provide a rotor with a hub in which the wipers or brushes are radially mounted to effect an even wear upon the track or race of the shell, and to provide springs peculiarly mounted in the hub for operation on the wipers or brushes to urge the same outwardly, and which may be easily positioned and removed to enable the quick detachment of the wipers or brushes from the hub and to maintain the wipers or brushes in the hub.

45 A still further object of the invention is to provide a rotor embodying all of the above characteristics and which comprises but few parts peculiarly constructed and assembled, which may be economically manufactured, and which may be applied to the timer shells now in use.

50 The above and various other objects and advantages of this invention will in part be described in and in part understood from the following detailed description of the present preferred embodiment, the same be-

ing illustrated in the accompanying drawing, wherein:

55 Fig. 1 is a vertical axial section of a timer in position on the timing gear shaft, and showing a rotor constructed according to the present invention applied thereto.

Fig. 2 is a transverse section taken through the same on the line 2—2 of Fig. 1.

60 Fig. 3 is a detail transverse section taken through the rotor showing the covering band in position and exposing but one group of the wipers or brushes.

65 Fig. 4 is a similar view with the band removed and the wipers or brushes in outward position, and

Fig. 5 is a detail perspective view of one of the wipers or brushes.

70 Referring to the drawing, 10 designates the forward end or wall of the engine and through which projects the usual timing gear shaft 11, and which has on its outer face the centering projection 12 within which is seated the timer shell 13. The shell 13 is held in place by a spring arm 14 carried upon a stud or post 15 projecting from the wall 10 and which has on its outer end a projection 16 adapted to seat in the depression at the apex 17 of the shell 13. The shell is provided with an arm 18 by means of which it may be shifted to advance and retard the timing action.

75 The rotor comprises a hub 19 adapted to fit the shaft 11 and which is provided at its outer end with preferably three radial slots 20 adapted to selectively receive the transverse pin 21 carried by the shaft 11, and over the end of the hub is adapted to fit 80 the usual cup washer 22 held in place by the locking nut 23 on the outer end of the shaft 11. The hub 19 at its intermediate portion is provided with spaced walls or disks between which is formed a chamber and which

85 carry between their confronting faces groups of wipers or brushes 24 arranged to slide radially with respect to the hub 19. Each wiper or brush 24 comprises a flat metallic piece suitably shaped at its outer end to 90 conform to the general cylindrical contour of the inner wall of the shell 13 and which at its inner end and in one side has a transverse seat or recess 25. The brushes 24 are 95 arranged in groups of any desired number 100 in close spaced apart relation, two in each

group being shown in the present instance, and are mounted in independent radial slots formed in the side plates or disks of the hub and are of sufficient length to project outwardly for contact with the shell 13 but which are adapted to be compressed into the hub 19 out of the way when desired.

Each pair of wipers 24 are mounted in the hub 19 with their seats or recesses 25 facing outwardly or away from each other so that the seat 25 of a brush of one pair faces the corresponding seat 25 of the brush of an adjacent pair. Between the pairs or groups of brushes 24 are placed leaf springs 26, one between each group and with the opposite ends of each spring 26 engaged in the seats 25 of the adjacent wipers 24. Thus, the wipers 24 of each pair or group are urged outwardly independently of one another. Each spring 26 is bowed outwardly at its intermediate portion and approaches the periphery of the hub 19, and the inner faces of the plates or disks of the hub are notched at 27 to receive a suitable instrument for withdrawing the springs 26, the notches extending inwardly at opposite sides of the springs so that access may be had therebeneath for withdrawing them. The hub 19 is provided with cross bars 28, one for each wiper 24 which extends across the outer side thereof to hold it in place, and inwardly tapering blocks 29 carried by the hub 19, one between each pair of wipers 24 to support and guide the same in the hub.

Only one group or pair of the wipers 24 is to be used at one time, and in order to maintain the remaining wipers 24 in retracted position out of the way, and to increase the tension of the springs 26 at opposite sides of the selected pair of wipers, a covering band 30 is employed. The band 30 is preferably of spring metal and is fitted in a depression 31 in the periphery of the hub 19 and is of such length that the ends of the band slightly overlap and terminate upon the bars 28 of the selected group of wipers. To prevent the ends of the band from shifting and binding against the selected wipers 24, the band has stop shoulders or lugs 32 upon its inner side and spaced slightly from the free end of the band, the shoulders 32 engaging the bars 28 to hold the band 30 from circumferential slipping. The band 30 bears against the outer ends of the remaining wipers 24 and retains them fully retracted and at the same time compresses the adjacent ends of the springs 26 and places the springs under greater tension to hold the selected wipers 24 in projecting position.

The selected wipers 24 are adapted to traverse the inner wall of the shell 13 and the embedded contact strips 33 which are connected to the binding posts 34. The wiping contact between the wipers 24 and

the contacts 33 insure the removal of the nonconducting film which forms upon the contacts, and the provision of a plurality of wipers 24 insures a good electrical connection through at least one of the wipers. 70 In turning, the first wiper may be utilized in removing the insulating film while the succeeding wiper 24 may form the desired contact. As the wipers 24 are mounted in true radial positions, and as they are independently spring pressed, they at all times follow the inner surface of the shell 13 and are effective in making an efficient contact in shells 13 even after the usual roller contacts have failed. The peculiar radial 75 mounting and spring tensioning of the individual wipers 24 prevent misfiring incident to the uneven or undulating surface on the inner wall of the shell 13, and which causes the roller contacts to jump or skip and thus 80 be kept out of contact with the fixed contacts 33 in the shell.

This novel rotor may thus be substituted in worn timer shells where the usual roller contact has failed to operate and will insure 90 the even firing of the charges in the cylinders of the engine and will facilitate the starting of the engine and reduce the fuel consumption.

As soon as one group of the wipers 24 is 95 worn down, the band 30 may be adjusted to expose a second group and depress the worn group. This adjustment may be effected from time to time until all of the groups of wipers 24 have been worn down, and the 100 provision of these various groups will thus materially increase the life of the rotor and will also serve to properly tension the springs and release the same sufficiently, by the removal of the band 30 as shown in Fig. 105 4 so that the springs may be easily removed and substituted and so that the wipers 24 may also be renewed.

What is claimed is:

1. A rotor for timers comprising a hub, a plurality of pairs of wipers mounted for radial sliding movement in the hub, springs disposed between the pairs of wipers and connected thereto for normally urging the same into projected position, and adjustable means for holding all but one group of said wipers.

2. In a rotor for timers, a hub, a pair of closely adjacent wipers mounted for radial sliding movement in the hub, and an independent spring carried by the hub for each wiper to independently and yieldingly maintain the same in projected position.

3. In a rotor for timers, a hub, spaced pairs of wipers mounted for radial sliding movement in the hub, a leaf spring mounted in the hub between each pair of wipers and engaging at opposite ends a wiper of each pair, and a spring band contractable upon the hub and having its ends spaced apart a 125 130

- distance sufficient to receive therebetween a single pair of wipers to admit free operation thereof and adapted to engage and hold retracted the remaining pairs of wipers to increase the tension of said springs. 5
4. In a rotor for timers, a hub, spaced pairs of radially slidable wipers mounted in the hub arranged for individual withdrawal therefrom and provided in their outer sides 10 with transverse seats, a leaf spring arranged between each pair of wipers and with its free ends engaged in said seats to normally urge the wipers outwardly independently of one another, and a spring band fitting on 15 the hub and against the outer ends of all but one pair of said wipers to maintain the same retracted and to increase the tension of the
- springs on said one pair of wipers whereby said pair of wipers may independently traverse the race of a timer shell. 20
5. In a rotor for timers, a hub, wipers mounted for radial sliding movement in the hub and disposed in spaced apart relation circumferentially of the hub, spring means normally urging said wipers radially and 25 outwardly with respect to the hub, and a spring band contractible upon the hub and having its ends spaced apart a distance sufficient to receive therebetween at least one of the wipers to permit free operation thereof 30 and adapted to engage and hold retracted other of the wipers.

CHARLES SABIERS.
